WILLIAM R. REYNOLDS, OF PASSAIC, NEW JERSEY

AUTOMATIC SNUBBING DEVICE

Application filed August 13, 1932. Serial No. 628,694.

This invention relates to an automatic device for snubbing a line, which may consist of a rope, cable, cord, band or the like.

The object of the invention is to provide a device of this character which combines both efficiency and compactness. It is so designed that the line to be used therewith may readily be pulled taut and automatically.

10 In the drawing accompanying this specification I have shown a preferred form and a number of modifications all of which however embody the same general principle of construction embodied in the preferred form.

Referring to the drawing, Figure 1 is a plan view showing the preferred form of the invention;

20 Figure 2 is a section on the line 2-2 of Figure 1;

Figure 3 is a view similar to Figure 1 but showing some of the parts in a different position;

25 Figures 4, 5 and 6 are details;

Figure 7 is a somewhat modified form of device; and

Figure 8 is a still further modification.

Referring to Figure 1, 2 is a base which may be in the form of a plate of suitable material and which also may be provided with screw holes 4 whereby it may be properly secured when the device is in use. Fixed to or forming part of the base is a member 6 preferably semi-circular. Pivoted adjacent the member 6 is a semi-heart-shaped member 8, the pivot 9 of which is preferably located as shown. The substantially straight working edges of these members are slightly separated when the pivoted member is in normal position, the edges being at this time substantially parallel to each other. The rounded surfaces of both members may be grooved as shown at 10 and 11 respectively in Figure 2, and the substantially straight working edges may also be grooved as indicated at 12, Figure 2.

40 The line or cord with which the device is designed to be used is indicated at 14 and is passed from the left-hand side, in Figure 50 1, between the working edges of the mem-

bers 6 and 8 and is then looped about the pivoted member 8 and the fixed member 6, whence it may pass through a guide 15 fixed to the base. Tension on the cord 14 in the direction of the arrow, Figure 1, results in the pivoted member 8 moving anti-clockwise about its pivotal point 9 and clamping the cord between its working edge and the working edge of the fixed member. If the cord is pulled in the other direction from a point such as A, it will run free. This is due to the placement of the pivot 9 at such a distance from the working edge that there is a moment of force tending to rotate the member 8 in a clockwise direction. If any pull however is exerted on the cord 14 in the direction of the arrow, the clamp immediately tightens and is securely held. If at any time it is desired to move the cord freely in the direction of the arrow the pivoted member 8 may be held away from the fixed member, and to facilitate this action, a lever 16 is pivoted at 17, said lever being provided with a cam face 18 adapted to bear against a pin 19 projecting from the pivoted member 8. The grooves 10 and 11 act as guides for the cord 14 and in addition there is provided a guide 20 carried by the base and in line with the working edges of the fixed and movable members.

80 By the arrangement shown a pull on the line at A acts in the same direction as the portion of the line indicated at 14. The guide 15 need not be located in line with the working edges of the fixed and movable members but may be located at any convenient place provided a tension in the direction of the arrow acts to bring the free end of the pivoted member toward the fixed member, or in other words, tends to rotate the pivoted member in an anti-clockwise direction about its pivot 9. In Figure 3 the lever 16 is shown in its operative position permitting the line to be readily moved in the direction of the arrow. Lever 16 may be arranged to act on the pin 19 from the opposite side, if desired.

85 The line or cord 14 has been shown as round in cross section in Figures 1 and 2, but it is apparent of course that it may take 90 100

other forms. Consequently the grooves 10, 11 and 12 would be correspondingly modified, and in Figures 4 and 5 I have shown such modified forms of grooves indicated by 5 11a and 11b and 12a and 12b respectively.

In Figure 6 a plane surface is shown, which in some instances may be preferable, as for instance if a narrow tape or belt were used.

Figure 7 shows a somewhat modified form 10 of the device. In this form the pivot 9a corresponding to the pivot 9 of Figure 1, is located outside of the working surface of the semi-heart-shaped member indicated as 8a. The working edges are also shown as 15 being slightly corrugated as at 22 so that a better grip may be had on the line. Corrugations may of course be used in any of the forms of device shown.

A further modification is shown in Figure 20 8, the fixed and movable members being indicated as 6b and 8b respectively. In this form of device rolling friction has been substituted for sliding friction, the cord 14 passing between the working edges of the 25 fixed and movable members and about a pulley 24 carried by the pivot 9b which may also be the pivot for the movable member 8b. The cord then passes about another pulley 25 carried by the movable member 30 8b at its free end; thence about a pulley 26 mounted on the base. Guides 15 and 20 serve the same function as these guides do in the construction shown in Figure 1. The pulley 24 is of such diameter that the moment of force tends to rotate the member 35 8b about its pivot 9b in a clockwise direction and thereby ease the pressure between the working edges to permit the line to run free.

40 What I claim as new is:—

1. In a device of the character described, in combination, a base, a member fixed thereto, a member pivoted to the base, said members having working edges between which 45 a line may be passed and looped about the pivoted member in the plane of its movement about its pivot and about the fixed member, and means to guide the line after it has been passed about the fixed member 50 whereby the line is clamped by said working edges when tension is applied to the end of the line beyond its contact with the fixed member.

2. In a device of the character described, 55 in combination, a base, a member fixed thereto and having a substantially straight grooved edge, a member pivoted to the base and having its pivotal point near one end of said fixed member and having a substantially straight grooved edge adjacent to but 60 separated from the edge of the fixed member, and a guide for the cord carried by the base near the loose end of the pivoted member, said pivoted member adapted to clamp 65 the cord between its edge and the edge of

the fixed member when the cord is looped about both members and is pulled about the fixed member in a direction to cause the pivoted member to move on its pivot toward the fixed member. 70

3. In a device of the character described, in combination, a base, a semi-circular member fixed thereto, a semi-heart-shaped member pivoted to the base adjacent the fixed member so that the straight edges of said members lie substantially parallel to each other but slightly separated when the pivoted member is in normal position, each of said members being peripherally grooved. 75

4. In a device of the character described, in combination, a base, a semi-circular member fixed thereto, a semi-heart-shaped member pivoted to the base adjacent the fixed member, said members having working edges between which a line may be passed and looped about the pivoted member and the fixed member, the construction and arrangement being such that the line is clamped by said working edges when the cord is pulled in a direction to cause the pivoted member to move toward the fixed member and means for moving the pivoted member to release the clamping action. 80

5. In a device of the character described, in combination, a base, a semi-circular member fixed thereto and having a groove in its rounded portion of such size and shape as to fit a cord or rope and having a shallow groove along its straight edge, a semi-heart-shaped member pivoted to the base adjacent said fixed member, said semi-heart-shaped member also having a groove in its rounded edge of similar shape and size to the aforesaid groove and a shallow groove in its straight edge, the pivoted member in normal position having its straight edge spaced slightly from the straight edge of the fixed member and adapted to clamp a cord between its edge and the edge of the fixed member when the cord is looped about both members and is pulled in the direction to cause the pivoted member to move towards the fixed member. 90

6. In a device of the character described, in combination, a base, a semi-circular member fixed thereto and having a groove in its rounded portion of such size and shape as to fit a cord or rope and having a shallow groove along its straight edge, a semi-heart-shaped member pivoted adjacent said fixed member, said semi-heart-shaped member also having a groove in its rounded portion of similar shape and size, and a shallow groove in its straight edge, the pivoted member in normal position having its straight edge spaced slightly from the straight edge of the fixed member and adapted to clamp the cord between its edge and the edge of the fixed member when the cord is looped about both members and is pulled in the direction 100 110 115 120 125 130

to cause the free end of the pivoted member to move towards the fixed member, and a guide for the cord carried by the base substantially in line with the straight portions of said members.

5 Signed at New York, N. Y., this sixth day of August 1932.

WILLIAM R. REYNOLDS.
